240,536

COMBINED AIR CONVECTOR AND LOG SUPPORT FOR FIREPLACES

Reuben L. Christophel, Harrisonburg, Va., assignor to
Shenandoah Manufacturing Company, Inc.

Filed June 5, 1975, Ser. No. 584,022

Term of patent 14 years

Int. Cl. D7—08; D23—03
U.S. Cl. D23—94

Fig-1

Fig-2

Fig-4

Fig-3

Fig-5

Fig-6

FIG. 1 is a perspective view of a combined air convector and log support for fireplaces, showing my new design;

FIG. 2 is a top plan view thereof;

FIG. 3 is a front elevation view thereof;

FIG. 4 is a side elevation view thereof, viewed from the right of FIG. 3;

FIG. 5 is a rear elevation view thereof; and

FIG. 6 is a bottom plan view thereof.

I claim:

The ornamental design for a combined air convector and log support for fireplaces, as shown.
